UNITED STATES PATENT OFFICE.

CALEB A. CARPENTER, OF GOUVERNEUR, NEW YORK.

BALL-PLAYER'S CLEAT.

1,118,920.

Specification of Letters Patent. Patented Dec. 1, 1914.

Application filed October 21, 1911. Serial No. 655,896.

To all whom it may concern:

Be it known that I, CALEB A. CARPENTER, a citizen of the United States, residing at Gouverneur, in the county of St. Lawrence and State of New York, have invented certain new and useful Improvements in Ball-Players' Cleats, of which the following is a specification.

My invention relates to an improvement in ball players' cleats, the object being to provide anti-slipping devices for sporting shoes, and in so doing to provide a device having the functions required of preventing the wearer's feet from slipping while affording flexibility and comparative ease and comfort.

In the accompanying drawings:—Figure 1 is a bottom plan view, and Fig. 2 is a view in side elevation. Fig. 3 is a perspective view of one of the cleats.

These cleats comprise a top flange 1, and a rib 2, which latter is V-shaped in cross-section to afford a cutting edge, and rounded at the ends as at 2, 2. The top flange is provided with holes 4, 4, to receive screws or other fastening means 5, 5, whereby the cleat or cleats are secured to the sole and heel of a shoe. These cleats may be in different lengths and dimensions according to the requirements as shown in Fig. 1, they being preferably screwed in place as illustrated in that figure, as this arrangement affords the greatest resistance to the sliding of the foot in all directions.

The arrangement of the cleats as shown in Fig. 1, permits of the sole of the shoe to be flexed, as a small space is formed between the adjacent cleats, and the diverging cleats are all provided with beveled inner ends, so that the ends of the adjacent cleats will not be brought into contact and prevent the flexing of the sole of the shoe. Furthermore, the diverging cleats form a means of obtaining a grip and prevent slipping. A better grip or hold can be obtained by having the sole of the shoe capable of flexing than is possible where the sole is rigid and in the majority of the cleats now in use, they are of a single piece of material and extend over a large portion of the shoe. With this invention I overcome this objection by providing a plurality of cleats and having them arranged around the sole

of the shoe with long and short cleats in a manner to obtain the best results and the greatest flexing of the sole.

When attached by means of screws, the cleats may be easily applied or removed at any time, as occasion may require.

The device is simple, inexpensive to manufacture, and easily applied, and is effectual in the performance of its functions.

More or less slight changes might be resorted to in the form and arrangement of the several parts described without departure from the spirit and scope of my invention, and hence I do not wish to be limited to the exact construction herein set forth, but:—

Having fully described my invention, what I claim as new and desire to secure by Letters Patent, is:—

1. An anti-slipping device for shoes, comprising a plurality of separate independent ribbed cleats mounted end to end on the sole of the shoe to follow approximately the perimeter of the sole, said cleats being formed at their ends in such a manner that they can be fastened in close proximity one to the other, and said cleats having the ribs thereof cut away or beveled at their ends in such manner as to allow contact of the cleats at the ends where they are in close proximity, and thus to permit free flexing of the sole.

2. An anti-slipping device for shoes comprising diverging cleats arranged on the toe of the sole, oppositely diverging cleats arranged on the sole in proximity to the instep, said cleats having their contiguous ends approximately at right-angles to the longitudinal extent of the sole, and cleats arranged between said divergent ends to be substantially parallel with said longitudinal extent.

3. An anti-slipping device for shoes comprising diverging cleats arranged on the toe of the sole, oppositely-diverging cleats arranged on the sole in proximity to the instep, said cleats having their contiguous ends approximately at right-angles to the longitudinal extent of the sole, and cleats arranged between said divergent ends to be substantially parallel with said longitudinal extent, the cleats of each diverging pair and the longitudinally-extending cleats made of

varying lengths and positioned on the sole in such relation that the contiguous ends or joints of the cleats are located to be beneath the ball and toe joints of the foot to 5 permit natural bending of the foot within the shoe.

In testimony whereof I affix my signature, in the presence of two witnesses.

CALEB A. CARPENTER.
